DESIGN FOR SHEARS OR SIMILAR ARTICLES

David C. Feather, Portland, Oreg.

Application February 10, 1937, Serial No. 67,563

Term of patent 14 years

To all whom it may concern.:

Be it known that I, David C. Feather, a citizen of the United States and a resident of Portland, in the county of Multnomah, State of Oregon, have invented a new, original, and ornamental Design for Shears or Similar Articles, of which the following is a specification, reference being had to the accompanying drawing, forming a part thereof.

Figure 1 is a perspective view of shears showing my new design.

Figure 2 is a plan view of the shears illustrated in Figure 1.

Figure 3 is a side elevation of the shears, the view being taken from the lower or right hand side of the shears as illustrated in Figure 2.

Figure 4 is a side elevation of the shears taken from the opposite side from that illustrated in Figure 3.

I claim:

The ornamental design for shears or similar articles substantially as shown.

DAVID C. FEATHER.
